US00D946844S

(12) **United States Design Patent** (10) Patent No.: **US D946,844 S**
Mathias et al. (45) Date of Patent: **** Mar. 22, 2022**

(54) **MOP REPLACEMENT HEAD**

(71) Applicant: **SharkNinja Operating LLC**,
Needham, MA (US)
(72) Inventors: **Richard Mathias**, Needham, MA (US);
Brandon J. Suleski, Cambridge, MA
(US); **Michael James Douglas**, London
(GB)

(73) Assignee: **SharkNinja Operating LLC**,
Needham, MA (US)

(**) Term: **15 Years**

(21) Appl. No.: **29/724,397**

(22) Filed: **Feb. 14, 2020**

(51) LOC (13) Cl. **07-05**

(52) U.S. Cl.

USPC **D32/39**

(58) **Field of Classification Search**

USPC D6/582; D30/159; D32/38, 41, 45, 49,
D32/50, 51

CPC A47L 9/1409; A47L 13/256; A47L 13/225;
A47L 9/1445; A47L 13/254; A47L 13/24;
B01D 50/002; B25G 3/38

CLAIM

We claim the ornamental design for the mop replacement head, as shown and described.

DESCRIPTION

FIG. 1 is an isometric view of the replacement head;
FIG. 2 is a front view of the replacement head;
FIG. 3 is a rear view of the replacement head;
FIG. 4 is a top view of the replacement head;
FIG. 5 is a bottom view of the replacement head;
FIG. 6 is a side view of the replacement head; and,
FIG. 7 is another side view of the replacement head.
Broken lines shown in the Figures indicate unclaimed subject matter.

1 Claim, 5 Drawing Sheets
